UNITED STATES PATENT OFFICE.

HENRY SCHNEIDER, OF TOTTENVILLE, NEW YORK.

DESIGN FOR A PUZZLE-BOX.

SPECIFICATION forming part of Design No. 26,229, dated October 27, 1896.

Application filed August 5, 1896. Serial No. 601,814. Term of patent 3½ years.

To all whom it may concern:

Be it known that I, HENRY SCHNEIDER, a citizen of the United States, residing at Tottenville, in the county of Richmond and State 5 of New York, have invented and produced a new and original Design for Puzzle Boxes or Cases, of which the following is a specification, reference being had to the accompanying drawings, forming a part thereof, in which—

10 Figure 1 is a plan view of a puzzle box or case, showing my design, and Fig. 2 a section on the line 2 2 of Fig. 1, these two views being necessary to fully illustrate my design.

15 The leading feature of my invention consists of a rectangular box or casing composed of a bottom 5, vertical side walls 6, and similar vertical end walls 7, and formed within said box or casing and secured to the bottom thereof are two elliptical vertical walls or 20 flanges 8 and 9, which are concentrically arranged and between which is a space 10, and within the vertical central wall or flange 9 is an elliptical space 11, and said elliptical ver-

tical walls or flanges 8 and 9 are connected near one end by a vertical partition-plate 12 25 and at one side by a transverse plate 13, at one end of which is a suitable plate 14, in the bottom of which is a port or passage 15, and adjacent to the opposite end of the plate 13 are three vertical pins or plugs 16, which are 30 arranged in the form of a triangle, the base of which is adjacent to the said plate 13.

Having fully described my invention, I claim as new and desire to secure by Letters Patent—

35 The design for puzzle boxes or cases, herein shown and described.

In testimony that I claim the foregoing as my invention I have signed my name, in presence of the subscribing witnesses, this 3d day 40 of August, 1896.

HENRY SCHNEIDER.
